UNITED STATES PATENT OFFICE

LEE M. WILSON, OF LOS ANGELES, CALIFORNIA

OPERATING SUPPORT

Application filed August 2, 1927. Serial No. 210,108.

This invention relates to improvements in operating supports or tables generally, and more particularly to a type of such supports or tables adapted for use by chiropractors and other practitioners in the performance of their manipulative or other operations on and adjustments of the human body.

The principal object of the invention is to provide for a support or table of the type set forth, and one of a mechanically refined construction and arrangement adapting it particularly for use as an essential part of the office equipment of a chiropractor or other similar practitioner, and which embodies certain novel features whereby to be quickly and easily set up for use, collapsed into compact form for storage, or for transporting from one point or place of use to another as may be desired or necessary from time to time.

With the foregoing and other equally important objects in view, the invention resides in the certain new and useful combinations, construction and arrangement of parts as will be hereinafter more fully described, set forth in the appended claims, and illustrated in the accompanying drawings, in which:

Figure 1 is a perspective view of a practical form of the invention,

Figure 2 is a vertical longitudinal section taken on the line 2—2 of Figure 1,

Figure 3 is a bottom plan view of the same,

Figure 4 is a vertical transverse section taken on the line 4—4 of Figure 2,

Figure 5 is a side elevation of the same when collapsed and ready for storage or transportation,

Figure 6 is a perspective view of one of the end sections of the apparatus, and showing the under side portion of the same and the manner of packing certain of the detachable or collapsible portions thereof,

Figure 7 is a similar view of the other of the end sections,

Figure 8 is an enlarged fragmentary vertical section taken on the line 8—8 of Figure 4,

Figure 9 is a similar sectional view taken on the line 9—9 of Figure 2,

Figure 10 is an enlarged fragmentary and longitudinal detail taken on the line 10—10 of Figure 3,

Figure 11 is a perspective view, partly in section, of a locking mechanism for securing certain of the movable parts of the device in adjusted position, and

Figure 12 is a perspective view of one of the detents or holding dogs of the locking mechanism.

Referring to the drawings, wherein similar characters of reference designate corresponding parts throughout the several views thereof, the support or table proper consists generally of three top sections 10, 11 and 12 disposed in longitudinal alignment and normally in a horizontal plane with respect to the floor level. The section 10 is preferably of a length substantially equal to the combined lengths of the sections 11 and 12, when the latter are disposed in their normally horizontal and end to end abutting positions. Each of these top sections 10, 11 and 12 are preferably upholstered on their upper sides and on their opposite side and end edges, substantially as shown.

The top section 10 is supported for a substantial portion of its length, inwardly from its outer end, on a boxing consisting of an outer end wall 13 and oppositely disposed side walls 14 and 15 secured at their outer ends to the opposite ends of the end wall 13. This boxing is, in turn, supported on outer oppositely disposed vertical legs 16 and 17 and inner oppositely disposed inclined legs 18 and 19. The outer leg 16 and the inner leg 18, at one side of the table, are connected together in properly spaced relations at their upper ends by a cross bar 20, and at their lower ends by a similar cross bar 21, while the pair of legs 17 and 19 are connected together at their upper ends by a cross bar 22. Immediately below this upper cross bar 22, of the legs 17 and 19, is another cross bar 23, the purpose of which will be hereinafter more fully explained. The outer legs 16 and 17 are hinged at their

upper ends, as at 24 and 25 respectively, to the inner faces of the side walls 14 and 15, immediately adjacent the corners formed of the connected ends of the latter with the end wall 13, while the inner legs 18 and 19 are similarly hinged, as at 26 and 27, to the inner faces of the inner semi-connected end portions of the side walls 14 and 15.

As shown in dotted lines in Figure 4, the complementary legs 16 and 18 are to be folded inwardly and upwardly to a horizontal position between the opposite side walls 14 and 15, and the opposite side legs 17 and 19 are to be similarly infolded to a position immediately beneath the legs 16 and 18, when desired, and after the lower cross bar 21 has been detached from the lower ends of the legs to which it is usually connected. To permit of this infolding of the opposite leg sections thus provided, the complementary legs 16 and 18 are slightly longer than the legs 17 and 19, and, as a consequence thereof, project for a correspondingly greater distance upwardly at the inner side of the adjacent side wall 14, so that the hinge connections of the same to the latter lie in a plane above that defined by the position of the hinge connections between the legs 17 and 19 with the inner side of the opposite side wall 15. A hook member 28 is pivoted to the outer side edge of the leg member 16 for engagement with a complementary eye or lug 29 carried by the leg 17, whereby to retain the leg sections in their nested or folded positions.

Extending between the side walls 14 and 15 adjacent their inner connected ends and spaced slightly below their top edges is a cross bar 30, which is preferably formed of a flat strip of metal having its opposite ends angularly bent downwardly to provide depending portions 31 and 32 disposed in abutting relation to the opposed surfaces of the side walls 14 and 15 to which they are secured by suitable fastenings 33. The top section 10 is secured to this cross bar 30 by means of the spaced hinges 34 and 35, and is sustained in its normally horizontal position on the top edges of the end and side walls 13, 14 and 15 by means of a hook member 36, pivotally secured on the under side of the top 10 and arranged for engagement with an eye or lug 37 secured in the inner surface of the end wall 13.

To sustain the oppositely disposed leg sections in set up position and against accidental infolding, a transversely disposed brace member or bar 38 is hingedly connected for horizontal hinging movement, as at 39, to the inner leg 18 and, when operatively disposed, has its other end abutted against the inner side of the intermediate cross member 23 carried by the complementary leg members 17 and 19. A keeper plate 40 is secured in position on the inner side

of this intermediate cross member 23 in line with the brace member 38, and is apertured, as at 41, to be engaged by the angularly bent end 42 of a sliding lock bar 43 mounted in oppositely arranged pairs of spaced guides 44 secured on one side of the brace member 38, when the angular end portion 42 is projected outwardly of the free end of the latter for the purpose. The inner end of the lock bar 43 is formed to provide an eye 45 in which a draw link 46 is pivotally engaged. This draw link 46 is also engaged over a draw lever 47, which is pivoted at one end, as at 48, to one end of an adjustable plate 49. This sliding plate 49 is formed to provide an intermediately disposed and longitudinally extending slot 50, which is engaged over the headed end of a lug or rivet 51 secured in the brace member or bar 38. The end of the sliding plate 49, opposite to its pivotal connection 48 with the draw lever 47, is angularly bent to provide for an outwardly extending portion 52 having a screw threaded aperture opening through the same for the engagement therein of an adjusting screw or bolt 53, which is also in threaded engagement with and extend through a complementally threaded aperture opening through an outwardly bent end portion 54 of a fixed plate member 55 secured in position on the brace member 38 by means of fastenings 56. The several parts of this locking mechanism are arranged in longitudinal alignment at one side of the brace member 38, substantially as shown in Figures 4 and 8, and the angular end 42, of the sliding lock bar 43, is to be moved into and out of engagement with the keeper plate 40 upon the proper manipulation of the draw lever 47, as will be readily obvious, while a proper adjustment of the parts will be easily effected by the operation of the adjusting screw or bolt 53. A stop 57, preferably in the form of a nut threaded on an intermediate portion of the adjusting screw or bolt 53, between the upturned portions 52 and 54, of the sliding plate 49 and the fixed plate 55, is provided to sustain the screw or bolt 53 in any desired position of adjustment, and to such end is to be moved into abutting relation to the adjacent side of the angular portion 54, of the fixed plate 55 for the purpose, after each adjustment of the screw or bolt 53 has been made. A resilient finger 58 is secured at one end, as at 59, to the sliding lock bolt 43, and is arranged to have its free end to bear against one side of the draw link 46 in a manner to force the latter toward the opposed face of the brace member 38, and to maintain the same generally in its aligned position of operation with the other parts of the locking mechanism. As shown in Figure 4, the brace members 38 is preferably made from a suitable length of substantially

U-shaped angle iron, whereby the parts of the locking mechanism, as above described, will be entirely within the channelled side of the same.

5 The top section 12 is similarly supported on the upper side of a boxing consisting of the end wall 60 and the oppositely disposed side walls 61 and 62, which are secured to the opposite ends of the end wall 10 60 at their outer ends. This boxing is, in turn, supported on outer oppositely disposed vertical legs 63 and 64 and inner oppositely disposed inclined legs 65 and 66. The outer end leg 63 and the inner leg 65, at one side 15 of the table, are connected together in properly spaced relation at their upper ends by a cross bar 67 and at their lower ends by a similar cross bar 68, while the opposite pair of legs 64 and 66 are similarly connected 20 together at their upper ends by a cross bar 69. Immediately below the upper cross bar 69 of the legs 64 and 66, is secured another cross bar 70. The outer leg members 63 and 64 are hinged at their upper ends, as at 71 25 and 72 respectively, to the inner faces of the side walls 61 and 62, while the inner leg members 65 and 66 are similarly hinged thereto by means of the hinges 73 and 74. The complementary legs 63 and 65, at one 30 side of the table, are to be folded inwardly and upwardly on their hinges 71 and 73 to a position transversely within the boxing after the manner of the leg members 16 and 18 of the other section of the table, and with 35 the lower cross bar 68 removed from the lower ends of the same. After these legs 63 and 65 have been so folded, the leg members 64 and 66 will also be infolded to a position immediately below the same, when 40 a latching device, similar to the hook 28 and the eye or lug 29 on the legs 16 and 17, will be applied to the legs 63 and 64 to secure the parts in folded position.

To sustain the oppositely disposed leg sections 63, 64 and 65, 66, in set up position, and against accidental infolding, a transversely disposed brace member 75 is hingedly connected for horizontal swinging movement, as at 76, to the inner side of the inner leg member 65 and, when operatively disposed, has its other end abutted against the inner side of the intermediate cross bar 70, carried by the complementary leg members 64 and 66. A keeper plate 77 (Figures 1 and 2) is secured in position on the inner side of the cross bar 70 in line with the brace member 75, and is apertured, to be engaged by the angularly bent end portion of a sliding lock bar 80 as in the preceding latch 45 means mounted in oppositely arranged pairs of spaced guides 81 secured on one side of the brace member 75, when the angular end portion 79 is projected outwardly of the free end of the latter for the purpose. The 50 inner end of this lock bar 80 is formed to provide an eye 82 in which a draw link 83 is pivotally engaged. This draw link 83 is also engaged over a draw lever 84, which, in turn, is pivoted at one end, as at 85, to one end of an adjustable plate 86. This adjustable or sliding plate 86 is formed to provide an intermediately disposed and longitudinally extending slot not shown which is engaged over the headed end of a lug or rivet 55 not shown secured in the brace member or bar 75. The end of this sliding plate 86, opposite to its pivotal connection 85 with the draw lever 84, is angularly bent to provide for an outwardly extending portion or lug not shown having a screw threaded aperture opening through the same for the engagement therein of an adjusting screw or bolt 90, which is also in threaded engagement with and extended through a complementally threaded aperture opening through 60 an outwardly bent end portion 91 of a fixed plate member 92. This plate 92 is secured in position on the brace member 75 by means of suitable fastenings 93. All of the several parts of this locking mechanism are arranged in longitudinal alignment at one side of the brace member 75, substantially as is shown in Figure 7, and the angular end 79 of the sliding lock bolt 80, is to be moved 65 into and out of engagement with the keeper plate 77, upon a proper manipulation of the draw lever 84, as in the first instance of the operation of this mechanism. The parts are to be properly adjusted by turning movements being imparted to the bolt or 70 screw 90, and are to be secured in adjusted position by means of a stop 94, preferably in the form of a nut threaded onto the bolt or screw 90, between the upturned portion of the plate 86 and the portion 91 and the 75 fixed plate 92, and to such end is to be moved into abutting relation to the adjacent side of the angular portion 91, of the fixed plate 92, for the purpose, after each 80 adjustment of the bolt or screw 90 has been 85 made. A resilient finger 95 is secured at one end to the sliding bolt 80, and is arranged to have its other end bear against one side of the draw link 83 in a manner to force the latter toward the opposed face 90 of the brace member 75 and to maintain the lock generally in its normal position of operation. As in the first instance of this bracing of the legs of the table supporting sections, the brace member 75 is made from a 100 suitable length of substantially U-shaped angle iron, with the locking mechanism housed within the channelled free end thereof.

The top 12, of the table or couch, is to be 105 fixedly secured in horizontal position on the top edges of the end wall 60 and the side walls 61 and 62 of the boxing formed thereby, as will be hereinafter more fully explained, while the intermediate top section 110

11 is hingedly connected, as at 96 and 97, directly to the inner side edge of the top section 12, and is normally supported in a horizontal plane common thereto and to the 5 top section 10. The inner side edge of the top section 12 is disposed in the vertical plane of the inner end edges of the side walls 61 and 62 of the boxing, so that the intermediate top section 11, by reason of its 10 hinge connections 96 and 97, with the top section 12, is free for unobstructed swinging movements in a downward direction between the top sections 10 and 12. The top section 12 constitutes the head and chest support 15 for a patient laid on the table or couch, the section 11 the abdominal support, and the section 10 the support for the lower extremities. To admit of the lengthening and shortening of the table, as shown in Figures 20 1 and 3, the lower cross or longitudinal bar 21, of the supporting legs 16 and 18, of the table or couch section supporting the top section 10, and the complementary cross or longitudinal bar 68 of the legs 63 and 65 of 25 the table or couch section supporting the top sections 11 and 12, are projected inwardly toward one another inwardly of the inner legs 18 and 65 respectively, and these projected end portions are provided at their extreme 30 inner ends with outwardly directed hook elements 98 and 99, which are arranged to engage over the intermediate portion of the top edge of a longitudinally extending connecting member or bar 100, which, in 35 turn, has inwardly directed hook elements 101 and 102 secured at its opposite ends for engaging the top edges of the bars 21 and 68 respectively. These several bars 21, 68 and 100 are supported on or immediately above 40 the floor surface, when properly positioned and connected, substantially as is shown in Figure 1. By this manner of sliding connection, the oppositely arranged table sections are slidable one relatively to the other, 45 whereby to be lengthened or shortened as may be necessary to accommodate persons of different heights.

As shown in Figure 4, when the opposite leg sections 16, 18 and 17, 19 are folded inwardly of the boxing formed by the end wall 13 and the side walls 14 and 15, the lower bar 21 is to be detached from the legs 16 and 18, and the brace member 38, together with the locking mechanism carried thereby, 50 is to be detached at its hinge connection 39 with the leg member 18, and these parts will be inserted endwise into the inner open end of the boxing above the leg section formed by the leg members 16 and 18. Similarly, 55 when the leg sections 63, 65 and 64, 66 are infolded within the boxing formed by the end wall 60 and the side walls 61 and 62, of the other table or couch section, the lower cross bar 68 and the brace member 75 will 60 be detached from normally operative posi-

tions, and will be nested within this latter boxing above the uppermost infolded leg section formed by the leg members 63 and 64.

Extending longitudinally and centrally beneath the top section 12 and the top section 11, is a bar 103, which is preferably in the form of a suitable length of inverted U-shaped channel iron, and has one end hingedly secured, as at 104, to the under side 70 of the top section 12 immediately inward of the end wall 60 of the upper boxing of this table section support, and its other end normally engaged in the inverted U-shaped channel of a guide bracket 105 secured on 75 the under side of the intermediate top section 11. The opposite side walls of the channel of the guide bracket 105 are in-turned to provide guide flanges 106 to support the opposite ends of a cross pin 107 80 carried in a loop 108' formed at the engaged end of the bar 103, whereby the cross pin 107 will have sliding movement on these in-turned flanges 106, when the top section 11 is depressed relative to the fixed top section 90 12.

Supported at their outer opposite ends in the complementary side walls 61 and 62, and arranged in transverse alignment beneath the inner edge portion of the fixed top section 12 to either side of the longitudinal bar 103, are a pair of fulcrum bars or rods 108 and 109, which have their inner opposed ends engaged in apertures formed in angular supporting brackets 110 and 111 respectively. Looped around the fulcrum bar or rod 108 are the intermediate portions of a pair of substantially parallel tension springs 112 and 113, which have their free ends at one side of the fulcrum bar movably engaged in 100 parallel guide channels or grooves formed in a guide plate 114 secured at the under side of the fixed top section 12, and their opposite free ends similarly engaged in parallel channels or grooves formed in another 105 guide plate 115 secured in proper position on the under side of the intermediate top section 11. Similarly looped around the fulcrum bar or rod 109 are the intermediate portions of a pair of substantially parallel 110 tension springs 116 and 117, which have their free ends at one side of the fulcrum bar or rod slidably engaged in parallel channels or grooves formed in a guide plate 118 secured at the under side of the top section 12, and their opposite ends in the channels or grooves of a complementary guide plate 119 secured on the under side of the intermediate top section 11.

To normally sustain the longitudinal bar 125 103 rigidly and to oppose any possible accidental downward swinging movement of the same on its hinge connection 104 and, consequently, to similarly prevent such accidental depression of the intermediate top 130

section 11 and its hinge connections 96 and 97 with the inner end edge of the top section 12, the lower edges of the flanged side walls of the bar 103 are engaged by the in-turned end portions 120' and 121' of a pair of detents or dogs 120 and 121 depending at opposite sides of the bar 103 from pivots 122 and 122' engaged in pairs of spaced ears 123 and 123' on the upper side of a supporting plate 124, the latter being provided with a suitably slotted opening beneath each of the pivots 122 and 122' through which the detents or dogs 120 and 121 operate. The supporting plate 124 is substantially U-shaped and has the top edges of its flange portions secured in abutting relation to the under side of the top section 12 by means of bolts or the like 125 being passed upwardly through aligned openings in the plate 124, the solid base portion of the top section 12, and a sustaining plate 126 resting on the upper side of the latter. The detents or dogs 120 and 121 are formed with arms 120'' and 121'' extending inwardly above their pivots 122 and 122' in alignment with and toward each other. The free ends of the arms 120'' and 121'' are preferably bevelled inwardly from small depending portions, substantially as shown in Figures 9 and 12, and have the latter engaged within the upper open end of a coiled spring 127 supported in vertical position centrally of the upper face of the supporting plate 124. This spring 127 acts at all times to tension the detents or dogs 120 and 121 toward operative positions. To effect a release of the detents or dogs 120 and 121 from locking engagement with the longitudinal bar 103, an operating rod 128 extends inwardly from the side wall 61 of the boxing support of the top section 12, and is journalled for necessary turning movements in the flanged portions of the supporting plate 124, an operating hand grip 128' being provided at its outer end, as shown in Figure 11. Secured on the rod 128 medially of the portion thereof extending between the side flanges of the plate 124, is an arm 128'' arranged to have its free end rest in overlying relation on the adjacent inner ends of the arms 120'' and 121'', of the detents or dogs 120 and 121, so that, when the rod 128 is turned, in proper direction, this end of the arm 128'' will be depressed and force the arms 120'' and 121'' downward against the tension of the spring 127. With the downward movement of their arm portions 120'' and 121'', the detents or dogs 120 and 121 are swung outwardly from the opposite sides of the bar 103 until their lower in-turned end portions 120' and 121' disengage from the lower edges of the depending flange portions of the longitudinal bar 103, when the latter bar 103 and the intermediate top portion 11 will be sustained in their normal horizontal posi-

tions by the action of the several springs 112, 113, 116 and 117. The detents or dogs 126 and 121 are identical in form, and, as shown in Figure 12, the detent or dog 120 has the free edge of its lower in-turned end portion 120' reduced in thickness by being bevelled at its lower side, whereby these reduced edges of both detents or dogs will be adjustably engaged either with the lower edges of the flanges of the bar 103 or any one of the several parallel grooves 103'' formed in vertical series in the outer faces of the said flanges. The lower end portion of each of the detents or dogs 120 and 121 are of substantial width, and, as shown in Figure 12, in connection with the detent or dog 120 only, the upper end portion of the latter is longitudinally split to provide pivot engaging ear portions 120'a which are twisted, as at 120'', into necessary parallel relation for the reception of the pivot in the aligned openings provided in the same for the purpose. The arm portion 120'' extends medially of the ear portions 120'a on a curved line outwardly and upwardly therefrom, and is then bent sharply in the reverse direction and into substantially right angular relation with respect to the lower body portions of the detent or dog, substantially as shown.

In the operation of the table or couch as thus constructed, the two end sections will be placed in alignment with the inner end edge of the top section 10 either abutted against the opposed end edge of the intermediate top section 11 or spaced therefrom, when the inwardly projecting and aligned lower bars 21 and 68 will be coupled by the longitudinal bar 100, which, when in place, will have intermediate portions of its top edge engaged by the hooks 98 and 99, of the bars 21 and 68, and the hooks 101 and 102 carried at its opposite ends, similarly engaged over the top edges of the bars 21 and 68 complementary thereto. As thus coupled, the opposite table or couch sections may be adjusted toward or away from each other by relative endwise sliding movements as occasion may require. When properly adjusted for length, a patient will be placed in recumbent position on the top sections, with his or her head and shoulders resting on the top section 12, the lower portion of the body or torso resting on the intermediate top section 11, and the extremities on the longer top section 10. In the initial placing of a patient on the table or couch, the intermediate top section 11 is preferably sustained in its normal horizontal position in the plane of the sections 10 and 12 by the supporting longitudinal bar 103 being locked against movement by the detents or dogs 120 and 121 engaging the same for the purpose.

For effecting certain manipulations or movements to the extremities of a patient,

the hook 36 will be disengaged from its keeper or eye 31, when the top section 10 will be free for vertical swinging movements on its hinge connections 34 and 35, and when its outer end is elevated, the inner end thereof will be lowered simultaneously. Similarly, if treatments are to be performed on the abdomen or the intermediate portions of the body, the operator will grasp the handle 128' and manipulate the same to turn the rod 128, when the arm 128" will depress the inner ends of the arms 120" and 121", of the detents or dogs 120 and 121, whereby the lower inturned end portions 120' and 121' of the latter will be disengaged from the lower edges of the flanges of the longitudinal bar 103, or from any one of the several grooves 103' in the outer faces of the said flanges. The bar 103 will now be free for downward swinging movements on its hinge 104, as will also be the intermediate top section 11 on its hinges 96 and 97, whenever necessary force is imparted to the stop section 11 to overcome the tension of the springs 112, 113, 116 and 117, which act to sustain the top section 11 and the bar 103 in normally disposed horizontal positions, or to return the same to such position after each downward swinging movements of the same.

When it is desired to again retain the top section 11 and the supporting bar 103 against movement, the rod 128 will be turned in a reversed direction, when the depressing action of the arm 128" will be removed from the spring 127, and, by reason of the expansion of the latter, the arms 120" and 121", of the detents or dogs 120 and 121, will be forced upward to normal horizontal position, and swing the latter on their pivots 122 and 122', when the lower inturned portions 120' and 121' will again engage with the lower edges of the side flanges of the bar 103 or with any one of the several grooves 103". In the engagement of the lower portions of the detents or dogs 120 and 121 with any one of their complementary grooves 103", the top section will be correspondingly sustained in a more or less of a depressed position depending upon which of the vertical sequence of the grooves 103" are so engaged.

To render the table or couch easily portable from one place of use to another, and with the supporting leg sections and the other detachable portions folded and nested within the supporting boxings beneath the top sections 10 and 12, substantially as shown in Figure 4, the two parts of the table or couch will be brought together with the inner open ends of the boxings disposed in abutting relation, and the projecting inner end portion of the top section 10 extending across and enclosing the open lower side of the supporting boxing of the top section 12, while the intermediate top section 11 is similarly extended alongside and encloses the

lower open side of the supporting boxing of the top section 10, substantially as shown in Figure 5. When assembled in this position, the parts or sections will be secured together by means of oppositely disposed fastenings 129 and a hand grip 130 will be provided at one side of the assembly for convenience in handling. This hand grip 130 is preferably provided at its opposite ends with snap hooks or the like 130', whereby it may readily attached to or detached from eyes or the like 130" secured in the outer faces of the side walls 14 and 61 of the supporting boxings of the top sections 10 and 12 respectively.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

Having thus fully described the invention what is claimed is:

1. An operating table comprising spaced horizontally adjustable base sections, a vertically movable top section carried by one of said base sections, a stationary top section carried by the other of said base sections, and an intermediate vertically movable top section carried at the inner end of said stationary top section, and means carried by one of said base sections for tensioning the vertical movements of said intermediate top section, comprising coil springs mounted on said stationary section and slidably engaging said movable section.

2. An operating table comprising a pair of spacedly aligned base sections adapted for relative endwise adjustments, a top section mounted for vertical tilting movements on one of said base sections, means for releasably securing said top section in normally disposed horizontal position, a stationary top section carried by the other of said base sections, an intermediate top section hingedly connected to said stationary top section and in slightly spaced relation with respect to said vertical tilting top section, said intermediate top section being adapted for tension opposed swinging movements between said base sections, and means for releasably securing said intermediate top section in adjusted substantially horizontal positions, comprising a supporting beam hinged on said stationary section and supporting said movable section and detent means for variably positioning said beam.

3. An operating table comprising oppositely disposed base sections, top sections carried by each of said base sections and projecting outwardly beyond the inner opposed ends of the same, legs carried by said

base sections and adapted to be folded inwardly thereof, said base sections being adapted to be abutted in end to end relation with the projecting end portions of each 5 of the said top sections overlapping the opposite lower sides of the adjacent of the base sections, means for securing said base sections together, and a carrying handle extending between said base sections at one 10 side thereof.

4. An operating table comprising oppositely disposed base sections, top sections carried by each of said base sections and projecting outwardly beyond the inner opposed 15 ends of the same, legs carried by said base sections and adapted to be folded inwardly thereof, said base sections being adapted to be abutted in end to end relation with the projecting end portions of each 20 of the said top sections overlapping the opposite lower sides of the adjacent of the base sections, means for securing said base sections together, and a carrying handle extending between and detachably connecting 25 said base sections at one side thereof in line with the adjacent of the said securing means.

5. An operating table, comprising a pair of spacedly aligned base sections, a top section mounted on one of said base sections, 30 a stationary top section carried by the other of said base sections, an intermediate top section hingedly connected to said stationary top section and in slightly spaced relation with respect to said first named top 35 section, said intermediate top section being adapted for tension opposed swinging movements between said base sections, and means for releasably securing said intermediate top section in adjusted substantially horizontal 40 positions, comprising a supporting beam hingedly mounted on said stationary section and slidably supporting said intermediate top section and detent means mounted on said stationary section for variably positioning said beam relative to said section.

6. An operating table, comprising a pair of spacedly aligned base sections, a top section mounted on one of said base sections, a stationary top section carried by the other 50 of said base sections, an intermediate top section hingedly connected to said stationary top section and in slightly spaced relation with respect to said first named top section, said intermediate top section being adapted 55 for tension opposed swinging movements between said base sections, and means for releasably securing said intermediate top section in adjusted substantially horizontal positions, comprising a supporting beam having 60 corrugated side walls hingedly mounted on said stationary sections and slidably supporting said intermediate top section and spring pressed detents adapted to engage the corrugations of said beams for variably positioning the same.

7. An operating table, comprising a pair of spacedly aligned base sections, a top section mounted on one of said base sections, a stationary top section carried by the other of said base sections, an intermediate top section hingedly connected to said stationary top section and in slightly spaced relation with respect to said first named top section, 70 said intermediate top section being adapted for tension opposed swinging movements between said base sections, and means for releasably securing said intermediate top section in adjusted substantially horizontal positions, comprising a supporting beam having corrugated side walls hingedly mounted 75 on said stationary sections and slidably supporting said intermediate top section, spring pressed detents adapted to engage the corrugations of said beams for variably positioning the same and manual means for releas- 80 ing said spring pressed detents.

8. An operating table, comprising oppositely disposed base sections, top sections carried by each of said base sections and projecting outwardly beyond the inner opposed 90 ends of the same, legs carried by said base sections and adapted to be folded inwardly thereof, said base sections being adapted to be abutted in end to end relation with the projecting end portions of each of the said 95 top sections overlapping the opposite lower sides of the adjacent sections of the base and means for securing said base sections together.

9. In an operating table, a base member, 100 a top section carried by said base member, a top section swingably mounted relative to said first named top section and means for adjustably supporting said swingable section comprising a corrugated beam swing- 105 ably mounted on said first named section and adapted to support said swingable top section and means on said swingable section for variably engaging said corrugated beam.
